UNITED STATES PATENT OFFICE.

FERDINAND KRONENBERGER, OF NEW YORK, N. Y.

RAIL SPIKE.

Application filed October 24, 1924. Serial No. 745,662.

This invention relates to spikes, and particularly to improvements in railroad spikes for causing said spikes better to engage the tie, and to be locked in place therein.

5 The various objects of the invention will best be understood from the description which follows and from the drawings, in which,

Fig. 1 is a side view of a railroad spike 10 of the usual type to which certain features of my invention have been applied.

Fig. 2 is a front view of the same.

Fig. 3 is a bottom plan view of the same.

Fig. 4 is a side elevation of a preferred 15 form of my invention.

Fig. 5 is a horizontal section on the line 5—5 of Fig. 4.

Fig. 6 is a horizontal section on the line 6—6 of Fig. 4.

20 Fig. 7 is a bottom plan view of that form of my invention shown in Fig. 4.

Fig. 8 is a side view of a spike embodying a modified form of end.

25 Fig. 9 is a similar view showing still another modification.

Fig. 10 is a bottom plan view of the spikes shown in Figs. 8 and 9, and

30 Fig. 11 is a vertical section of a railroad rail showing one of my improved spikes in position and another about to be driven down into the tie.

It is well known that if the fibres of a 35 wooden tie have been cut completely across by the end of the spike as said spike is driven into said tie, the cut ends of said fibres are bent downwardly and frictionally resist the lifting out of the spike.

If the fibres have not been cut, the spike 40 forces said fibres apart and splits the tie on its way thereinto. The life of a tie depends largely on the number of splits or checks therein. If a tie is not split, comparatively little moisture reaches the interior thereof and the wood is not exposed to the rotting 45 action of the water. If, however, there should be any splits or checks in the tie, the tie rots rapidly and the spike will no longer hold, since the fibres have not the strength to resist any withdrawing force 50 exerted on said spike.

55 My improved spike is designed to cut its way through the fibres, and to allow the cut ends of said fibres to expand into suitable spaces in the spike whereby more resistance is offered to the withdrawal of the spike than is otherwise possible.

In the simplest embodiment of my invention, illustrated in Figs. 1, 2 and 3, the front and rear faces 10 and 11 of the straight spike 12 have shallow, inclined grooves 13 60 therein, of predetermined pitch. Each of said grooves preferably comprises a face 14 having downward pitch to the right as viewed in Fig. 2, and lying in a plane substantially perpendicular to the faces 10 and 11. Said face 14 enters the spike for a short distance, and meets a similarly inclined face as 15 joining the bottom of said grooves 13 with the face 10 or 11 of said spike. It will be understood that the angular relation of said groove faces 14 and 15 to each other and to the plane of the spike faces 10 and 11 may be varied as desired. Said grooves 13 serve to receive the 70 cut ends of those of the fibres which are free to expand into said grooves after the spike has been driven home. If it is attempted to withdraw the spike by a longitudinal pull, the ends of those of the fibres in the grooves tend to follow the bottom of the groove, and tend further to cause the spike to twist in the tie, or if the twisting action is prevented in any manner, said fibre ends resist the pulling action and tend to maintain the spike in place in the tie, 75 since the withdrawing force exerted on the spike must otherwise be sufficiently great to bend the fibre ends upward by a sufficient amount to draw said ends out of the grooves 13.

80 In those forms of my invention illustrated in Figs. 4 to 11 inclusive, the spike is intended to be used in connection with a tie plate 16 of the usual type, in which a preferably square hole as 17 is provided in the usual manner. It will be noted that said spikes are twisted to about a quarter turn or somewhat less, so that as the spikes are driven into the tie, said spikes are forced by reason of the contact thereof with the side of the hole 17, to rotate through an angle equal to the twist of the spikes. It will also be noted the twist begins at a point in the shank sufficiently below the head 27 to allow said shank to engage the hole 17 in 90 the plate in the usual manner.

95 As illustrated in Figs. 4, 5, 6 and 11, the spike 18, which embodies the preferred form of my invention, is grooved on the faces 19 thereof by means of the substantially helical 100 or inclined grooves 20, similar to the grooves 13 above described, the pitch of which is

preferably, though not necessarily the same as that of the twist in the spike, but which pitch is opposite in direction to said twist. Said spike 18 terminates preferably in a 5 point 21, which may be rounded, as shown, into substantially conical form, if desired, to allow said spike more easily to enter the tie, though the conical point may be dispensed with. The helical edges 22 of the 10 spike in which the faces of said spike meet are continued toward the point 21, while each of the faces 19 near said point are indented or undercut by the reentrant surface 23 without disturbing the curvature of 15 said edges 22, whereby said edges are sharpened substantially into helical knife edges 25 continuous with the spike edges 22.

It will be noted that a line joining the innermost surface of the portions 23 would 20 be substantially parallel to the helical edges 22, though it will be understood that said portion 23 may be formed by a pair of substantially flat cuts meeting in a sharp helical edge, if desired.

25 When it is desired to drive the spike 18 into the tie the head 27 thereof is turned about one-quarter turn away from the rail, and is then driven in in the usual manner. An overhanging round end of the usual 30 type however may be used instead to obviate the necessity of starting the spike in this position. The point 21 cuts and compresses the fibres on its way into the tie, while the knife edges 25 cut the ends of the 35 fibres across, along a helical line beginning near the top of the tie and extending downwardly to the end of the spike. Since the fibres are cut, the tendency of a spike to split the wood on its way thereinto, is minimized without making a large hole in the tie. The cut ends of the fibres expand into the grooves 20 in the manner hereinbefore 40 explained in connection with the form of my spike shown in Figs. 1 and 2. As the spike progresses into the tie, the fibres which are cut by the knife edges 25 follow the bottom of the cuts forming said knife edges, and are gradually spread apart and slightly 45 compressed until they reach their final position in one of the grooves 20. It will be noted that the spike is forced to turn by reason of its engagement with the sides of the hole 17 in the tie plate 16 in its downward progress, and for the same reason the spike 50 cannot be withdrawn from the tie without being turned in the opposite direction.

In that form of my invention shown in Fig. 8, the end 28 instead of being pointed as in the spike 18 or bevelled as in the spike 55 12 is sharpened by means of the grooves 29 into a series of chisel edges 30, whereby the fibres are cut when the spike is driven into the tie and the cut ends of the fibres forced

to follow the line 31 at the juncture of the surfaces 32 and 33 forming said chisel edges. 65 In that form of spike shown in Fig. 9 the chisel edges 34 are inclined slightly upwardly in order that the spike may be readily started into the tie.

The various embodiments of my invention 70 shown herein are intended to be merely illustrative, since changes in the structure presented herein may readily be made without departing from the spirit and scope of this invention within the term of the appended 75 claims.

I claim:

1. In a rail spike of substantially square cross section, substantially helical edges extending lengthwise of the spike, a pair of 80 reentrant surfaces inclined to said edges extending across the faces of said spike and meeting to form a continuous groove therein at a pitch substantially equal but opposite in direction to the pitch of the helical 85 edges of said spike.

2. A rail spike comprising a twisted shank square in cross-section substantially helical edges on said shank, a tapered lower end on 90 said shank, and substantially helical cutting edges continuous with the helical edges of said shank at the lower end of said spike, the faces of said shank having continuous, helical grooves therein substantially of the same pitch but opposite in direction to that 95 of the edges of said shank.

3. In a twisted rail spike of substantially square cross-section, reentrant surfaces extending inclinedly across the faces of said spike for forming continuous helical grooves 100 therein of opposite pitch to that of the edges of said spike, and surfaces near the lower extremity of said spike undercutting said edges for forming cutting edges at said lower extremity.

4. A rail spike comprising a shank twisted from the lower extremity thereof to a point spaced from the upper end of said spike, and surfaces near said lower extremity undercutting the edges of said spike for sharpening said edges into cutting edges, the faces of said shank having continuous helical grooves therein, the pitch of said grooves being substantially the same as, but opposite in direction to that of the twisted edges of 110 said shank.

5. In a rail spike, a shank square in cross section, helical edges on said shank from the lower end thereof to a point below the upper end thereof, the lower parts of said edges being sharpened into cutting edges, and the faces of said shank being diagonally grooved to form continuous helical grooves of substantially the same pitch as 120 said helical edges, but opposite in direction.

FERDINAND KRONENBERGER.
